UNITED STATES PATENT OFFICE.

HORACE EMMERSON MARTIN, OF ATHENS, GEORGIA.

CHAIN SAW.

1,150,217.

Specification of Letters Patent. Patented Aug. 17, 1915.

Application filed October 6, 1914. Serial No. 365,322.

To all whom it may concern:

Be it known that I, HORACE E. MARTIN, a citizen of the United States, residing at Athens, in the county of Clarke and State of Georgia, have invented certain new and useful Improvements in Chain Saws; and I do hereby declare the following to be a full, clear, and exact description of the invention, such as will enable others skilled in the art 10 to which it appertains to make and use the same.

This invention relates to chain saws adapted for use on portable and other sawing machines for cutting green wood and growing trees; and it consists in the novel construction and combination of the parts hereinafter fully described and claimed.

In the drawings, Figure 1 is a side view of portions of a chain saw constructed according to this invention. Fig. 2 is a similar side view with one row of side links and cutting teeth removed, the outline of the hidden portions of the cutting teeth of the other side links being shown in dotted lines. Fig. 3 is a plan view of the portions of the chain saw shown in Fig. 1. Fig. 4 is a cross-section, taken on the line $x-x$ in Fig. 1. Fig. 5 is a side view of portions of a chain saw with some side links removed, and showing 30 a modification in which the cutting teeth are formed on adjacent pairs of side links, and the gage teeth are formed in sections.

The chain saw is adapted to be supported on a frame or sawing machine of any approved construction, and it may be driven by hand or by power in any approved way.

In the preferred form of the saw two kinds of side links 2 and 3 are provided, and are arranged in pairs alternately of each 40 other. The side links 2 are connecting and supporting links, and they are not provided with cutting teeth. The side links 3 have cutting teeth 5, and these cutting teeth preferably project forwardly over the front end 45 of the links to which they pertain. The cutting teeth are made in various shapes or curves in carrying out this invention. The front portions 4 of the shanks of the cutting teeth are curved and they rest against the 50 upper rear end portions of the connecting links 2.

Each side link, 2 and 3, has an inclined projection 6 at its rear end, which overlaps an inclined projection 7 on the front end of

the next adjacent link and prevents the saw 55 from bending in one direction.

Two kinds of center links 8 and 9 are provided, and they are arranged alternately. The center links 8 are provided with forwardly projecting drag teeth or planer teeth 60 12, the side portions 14 of which are wider than the links 8 so that they form stops which rest on the tops of the connecting side links 2.

The drag teeth links 8 are pivoted to the 65 front end portions of the connecting side links 2, and to the rear end portions of the side links 3, by pivot pins 15. The drag teeth are hook-shaped, and they have rearwardly and upwardly inclined shanks 16. 70

The center links 9 are provided with gage teeth 17. The center links 9 are pivoted to the rear end portions of the connecting side links 2, and to the front end portions of the side links 3, by pins 18. The gage teeth 17 75 project longitudinally over each end of their links 9, and they have upwardly and rearwardly inclined tops 10. The front end portions 19 of the gage teeth are curved and they rest upon the curved lower portions of 80 the drag or planer teeth 12 and their shanks.

The front and pointed ends of the gage teeth are arranged in line with the front and pointed ends of the cutting teeth 5, at the bottom of their cutting portions, which 85 bottoms are indicated by the dotted lines 11 in Fig. 2. The rear ends of the gage teeth have beveled portions 13 which underlap the beveled front ends of the drag teeth 12. The rear ends of the gage teeth are arranged a little below the level of the cutting 90 edges of the drag teeth, and they prevent the drag teeth from taking too great or rank a hold on the kerf in the saw cut. The front end portions of the gage teeth limit 95 the depth of the cut of the slicing or cutting teeth 5.

By making the gage teeth 17 with beveled ends and arranging them as set forth, each gage tooth forms an efficient and positive 100 gage for two cutting teeth 5 and for the drag tooth 12 next following them.

The front end portions of the cutting teeth 5 have curved portions 20 which rest upon the curved lower portions and shanks 105 of the drag or planer teeth 12, so that the drag teeth are reinforced and supported by the front end portions of both the gage teeth

and the cutting teeth. The curved portions 20 are preferably formed separate from the curved portions 4, so that they intersect where they meet, in order that the cutting 5 teeth and the gage teeth may be stronger and lighter and better proportioned; but the curves of these curved portions may be made continuous, as shown in Fig. 5, if desired.

10 All the center links have downwardly projecting lugs 22, or other approved means, for engaging with the driving mechanism of the sawing machine. The various overlapping portions of the links and the 15 shanks of their teeth prevent the saw from bending in one direction, when the saw is straight; and permit it to bend, or turn on its link pivots, in the opposite direction. They also stiffen the saw, and prevent it 20 from vibrating, so that it can be used to cut green wood or lumber to advantage.

In the modification shown in Fig. 5, the general structure is the same as hereinbefore described, but instead of the single pairs of 25 cutting teeth 5, the saw is provided with two pairs of cutting teeth 55 arranged adjacent to each other and pivotally connected together. Instead of the gage teeth 17, similar gage teeth formed in two sections 30 27 and 37 are provided. These two sections are pivotally connected together, and these two sections are provided for the accommodation of the two pairs of cutting teeth 55. The curved front end portions 19 are 35 formed on the front sections 27, and the beveled end portions 13 are formed on the rear sections 37. In this form of saw, increased slicing action is provided in propor-

tion to the planing action of the drag teeth, but otherwise the action is the same as that 40 of the saw shown in Figs. 1 to 4.

What I claim is:

1. In a chain saw, the combination, with side links provided with forwardly projecting cutting teeth, of center links pivoted to 45 the side links and provided with forwardly projecting drag teeth having beveled cutting portions, and having also gage teeth each provided with an upwardly and rearwardly inclined top which extends from the 50 lower parts of the cutting portions of two cutting teeth to a point a little below and in front of the sharp cutting edge of the next following drag tooth, said gage teeth having beveled end portions which underlap 55 the beveled cutting portions of the drag teeth.

2. In a chain saw, the combination, with side links certain of which are provided with cutting teeth, of center links pivoted to the said links, certain of the center links being provided with drag teeth and other center links being provided with gage teeth each formed of two pivotally-connected sections, said sections having continuous upwardly and rearwardly inclined tops which extend rearwardly from between the cutting teeth to a point adjacent to the cutting edge of the next following drag tooth.

In testimony whereof I have affixed my 70 signature in the presence of two witnesses.

HORACE EMMERSON MARTIN.
